UNITED STATES PATENT OFFICE

98,851

DESIGN FOR AN INSECT EXTERMINATOR

Claude E. Canning, Wilmette, Ill., assignor to
C. E. Canning, Incorporated, Chicago, Ill., a
corporation of Illinois

Application November 13, 1935, Serial No. 59,525

Term of patent 7 years

To all whom it may concern:

Be it known that I, Claude E. Canning, a citizen of the United States, residing at Wilmette, in the county of Cook and State of Illinois, have invented a new, original, and ornamental Design for an Insect Exterminator, of which the following is a specification, reference being had to the accompanying drawing, forming part thereof.

The single figure of the drawing illustrates in perspective an insect exterminator embodying my new design.

The concealed side and end of the device are

the same as the side and end illustrated, except that the projecting knob element is omitted from the opposite end.

My new design is characterized by an elongated supporting member having spaced box-like casings mounted near its ends and between which a generally cylindrical arrangement of the insect exterminating elements extend.

I claim:

The ornamental design for an insect exterminator, substantially as shown and described.

CLAUDE E. CANNING.
